PULL ROD CONNECTION

Elmer R. Thomas, Healdton, Okla., and David Erickson, Wichita Falls, Tex.; Selma E. Erickson, executrix of said David Erickson, deceased; said Selma E. Erickson, executrix, assignor to H. L. Ayers and H. K. Ayers, comprising the partnership of Wichita Wire & Iron Company, Wichita Falls, Tex.

Application February 16, 1942, Serial No. 431,154

8 Claims. (Cl. 287—124)

This invention relates to improvements in pull rod connections of the character used for attaching the pull rods of oil well pumps and the like to eccentric motions which operate the same.

The oil well pumps are operated frequently from an eccentric motion power unit which drives a plurality of pull rods. After a pump has forced out the accumulated oil in the well, it is desired to release the pull rod thereof from the eccentric motion while the well is filling, to prevent the idle operation of the pump, which may be injurious to the oil. It has been customary to connect the pull rod with the eccentric motion by a C-link to permit release of the rod, but this required manual grasping of the link to release it. Since the releasing action must take place during the reciprocating movements of the pull rods, this often results in injury to the hands or person of the operator.

The object of this invention is to improve the construction of the connection between the pull rod and the eccentric motion to facilitate ready removal or release of the pull rod therefrom without danger of injury, and also to permit the parts to be connected without difficulty whenever desired.

This is accomplished by constructing the connecting means with a holding pin for a pull rod link, which may be released manually by a handle connected therewith without danger of injury to the operator, which handle also facilitates the reconnection of the parts whenever desired.

The invention also includes an improved D-link which has sliding connection with the pull rod to permit retraction relative thereto out of the path of operation of the connecting means attached to the eccentric motion, and which may be drawn out for connection therewith when it is desired to operate the pull rod.

A preferred embodiment of the invention is illustrated in the accompanying drawings in which:

Fig. 1 is a top plan view of an eccentric motion power unit and pull rods, having the invention applied thereto;

Fig. 2 is an enlarged transverse sectional view through the connection body, on the line 2—2 of Fig. 1;

Fig. 3 is a top plan view thereof with the handle in released position;

Fig. 4 is a longitudinal sectional view thereof, showing the handle and pin in engaged positions;

Fig. 5 is an end elevational view of the body;

Fig. 6 is a top plan view of the D-link and clamps;

Fig. 7 is a side elevation thereof;

Fig. 8 is a transverse section therethrough on the line 8—8 of Fig. 6; and

Fig. 9 is a similar view looking in the opposite direction, taken on the line 9—9 of Fig. 6.

The invention is shown in Fig. 1 as applied to a plurality of pull rods which are operated from a single power unit 1 driving the eccentric motion 2. The pull rods which radiate from the power unit eccentric motion are designated generally by the numeral 3, and extend therefrom to the respective well pumps for operating the same.

Each pull rod 3 is shown as connected with the eccentric motion 2 by a clevis 4 which has a link 5 secured thereto at one end. The opposite end of the link 5 is attached to a connection body 6, as shown in Figs. 4 and 5. One end of the body 6 has a V-groove 7 therein which has tapering sides, as shown in Fig. 5, to accommodate links of different diameters, as indicated in dotted lines in Fig. 5. At the inner end of the V-groove 7 is a recess 8 receiving a head 9 formed on the link 5, and the link 5 is clamped securely in the V-groove 7 by a bar 10 which extends thereover behind a shoulder 11 (see Fig. 4). Bolts 12 extend through the bar 10 and the body 6 to secure the former in place and thereby hold the link 5 against slipping loose from the body, while the head 9 prevents it from pulling out in the event that the rod should become loose.

The body 6 has a longitudinal passageway 13 extending into the opposite end thereof from the link 5 to receive therein a D-link 14. The D-link 14 may be pushed forward relative to the body 6 until its forward end abuts against the forward end 15 of the passageway 13. A pin 16 is adapted to secure the D-link 14 to the body 6, as indicated in Fig. 4.

The pin 16 is pivotally supported at 17 on an arm 18 which is carried by a handle member 19. The handle member 19 is pivotally supported at 20 between upstanding ears 21 on the body 6, which pivot 20 is intermediate the major portion 45 of the handle 19 and arm 18 laterally offset therefrom, as shown in Fig. 4. The handle member 19 also has an offset heel portion 22 in position to abut against the surface 23 at the upper side of the body 6 to limit the swinging movement of the handle member 19 when it is turned from its full line to its dotted line position in Fig. 4. When thus lowered, the handle member holds the pin 16 in a raised position, releasing the D-link 14 for disconnection of the pull rod 3, as shown in Figs. 6 to 9, to permit the D-link to be retracted

on the pull rod when the latter is released from the eccentric motion as shown in the lower portion of Fig. 1, and in Figs. 6 and 7. For this purpose, the pull rod 3 has a clamp designated generally at 24, shown as two-part construction, with the sides embracing the end of the pull rod 3 behind the head 25 thereof, and secured thereto by clamping bolts 26. The clamp 24 has grooved portions 27 on opposite sides of the pull rod 3, slidably receiving the sides of the D-link 14, as shown in Fig. 9.

A similar two-part clamp 28 is secured by bolts 29 rigidly to the arms of the D-link 14 behind the heads 30 on said arms for holding said clamp 28 securely thereon. The clamp 28 has a grooved portion 31 slidably receiving the pull rod 3 and loose relative thereto, as shown in Fig. 8. An upstanding handle 32 is secured also to the clamp 28 to facilitate forward movement of the D-link 14 relative to the pull rod.

During normal operation of the oil well pumps, the parts are connected as shown in the upper portion of Fig. 1. When it is desired to disconnect a pull rod, as shown in the lower portion of Fig. 1, it is first necessary to insert a knock-off block 33 over the pull rod 3 against the knock-off post 34 and between the latter and the usual pull rod clamp 35. Then it is only necessary for the operator to grasp the handle 19 and swing the same down to the dotted line position in Fig. 4, which may be done during the operation of the power unit eccentric motion without danger of injury to the operator. This raises the pin 16 out of holding engagement with the D-link 14, permitting the latter to be disconnected from the body 6 and allowing said body to continue its motion with the power unit. The operator then grasps the handle 32 and slides the D-link 14 back on the pull rod 3 to its retracted position out of the path of movement of the connection body 6 under the influence of the eccentric motion. Thus, the parts may be readily disconnected in a very simple fashion without danger of injury to the workman, and the connecting link is withdrawn so as to eliminate danger of its being struck by the operating connection body during the continued operation of the eccentric motion, which might cause injury to the parts or release of the pull rod accidentally from the knock-off post.

When it is desired to reconnect the pull rod with the eccentric motion, the operator may grasp the handle 19 and raise the same to the full line position in Fig. 4. While holding the handle in this position with one hand, he may grasp the handle 32 with the other and thereby guide the D-link 14 into the passageway 13 of the connection body 6. The pin 16 will swing upon its pivot 17 to permit the insertion of the D-link 14 and then drop by gravity into the slot of the D-link, holding the D-link against being withdrawn therefrom. The pin 16 abuts against shoulders 46 on the body 6 at the top and bottom of the passageway 13 to form a secure connection of the D-link with the body. This reconnection is accomplished also without danger of injury to the operator, and upon removal of the knock-off block 33, the pull rod 3 may be operated as before.

We claim:

1. In a well pump operating structure, the

combination with a power unit, and a pull rod, of a connection between said power unit and pull rod, said connection comprising a link and a body, one being connected with the power unit and the other being connected with the pull rod, said body having a passageway therein slidably receiving the link, a pin detachably engaging the link, and a handle pivoted to the body and pivotally connected with the pin for releasing the pin from the link.

2. A pull rod connection comprising a body having a passageway adapted to receive a link therein, a pin for detachably engaging said link, and a handle pivoted to the body and pivotally connected with the pin for releasing the pin from the link.

3. A pull rod connection comprising a body having a passageway adapted to receive a slotted link therein, a pin for detachably engaging in said link, a handle pivoted to the body and pivotally connected with the pin for releasing the pin from the link and means for limiting the swinging movement of the handle.

4. A pull rod connection comprising a body having a passageway therein at one end thereof, a D-clamp having a slotted portion inserted into said passageway, a pin extending transversely through said slotted portion, a handle member pivoted to said body and having the pin pivotally connected therewith for supporting said pin, means on said body at opposite sides of the passageway forming abutments for said pin, and means for limiting the swinging movement of the handle member.

5. A connecting link comprising a link body having a transverse clamp fixed thereon, said clamp having a guideway for slidably receiving a pull rod, and a second clamp slidably mounted on the link body and having means for securing the same to the pull rod.

6. A D-link comprising a link body having spaced sides, a transverse clamp extending in bridging relation between said sides and rigidly fixed thereto, said clamp having an intermediate guideway for slidably receiving a pull rod, and a second clamp extending in bridging relation between the sides of the link body and slidably mounted thereon, said second clamp having means for securing the same to the pull rod.

7. A pull rod connection comprising a body having a passageway therein adapted to receive a link, a pin for detachably engaging said link, means forming shoulders at opposite sides of said passageway, and means mounting said pin transversely of the passageway with opposite end portions thereof bearing laterally against said shoulders, said mounting means being constructed for movement of the pin out of engaged position with the link.

8. A pull rod connection comprising a body having a passageway therein adapted to receive a link, a pin for detachably engaging said link, means forming shoulders at opposite sides of said passageway, and means mounting said pin for swinging movement transversely of the passageway to a link engaged position with opposite end portions thereof bearing laterally against the shoulders.
